UNITED STATES PATENT OFFICE.

LEROY F. HARZA, OF CHICAGO, ILLINOIS.

HYDRAULIC TURBINE.

Application filed December 18, 1922. Serial No. 607,551.

To all whom it may concern:

Be it known that I, LEROY F. HARZA, a citizen of the United States, residing at Chicago, in the county of Cook and State of Illinois, have invented certain new and useful Improvements in a Hydraulic Turbine, of which the following is a specification.

My present improvements relate to hydraulic turbines, and more particularly to the axial flow type disclosed in my application for U. S. Letters Patent filed on the 24th day of November, 1919, Serial No. 340,137, patented Feb. 26, 1924, #1,485,186.

In this type of turbine the band or rim of the turbine forms a portion of the water pipe, or conduit, and revolves with close clearance between the fixed ends of those portions of said conduit which lead to and from the turbine, generally known as the penstock and draft tube, respectively. My invention, however, is not limited to this type of turbine, inasmuch as certain features thereof are equally applicable to the usual form of axial flow turbine, in which the runner is constructed without a band and revolves within a closed continuous pipe, or conduit.

One of the objects of the present invention is to provide central bearings for the turbine runner and means whereby the same may be regulated and adjusted to secure and maintain the requisite alignments of the shaft.

Another object is to provide means associated with the bearings affording provision for the mounting of radial regulating gates by which the flow of water to the runner may be regulated.

A further object is the provision of improved means for simultaneously moving the controlling gates toward open or closed position.

Still another object is the provision of means for facilitating the drainage of leakage water from the clearance between the turbine and the adjacent penstock and draft tube.

Other objects and many of the attendant advantages of my invention will be readily appreciated as the same becomes better understood by reference to the following description, when considered in connection with the accompanying drawings.

Referring to the drawings:

Fig. 1 is a longitudinal section of an axial flow turbine embodying my invention;

Fig. 2 shows a similar installation ap-

plied to an axial flow turbine without a rim and revolving entirely within a closed water-trunk;

Fig. 3 shows an arrangement similar to Fig. 1 except that the thrust bearing is positioned downstream from the turbine or in the draft tube;

Fig. 4 shows an arrangement similar to Figs. 1 and 3 except that the thrust is taken by the rim of the turbine against a bearing seat in the rim of the draft tube.

Fig. 5 is a fragmentary sectional view showing the structure for operating the control gates and also the method of draining of the leakage in Figs. 1 and 3;

Fig. 6 is an enlarged view of the thrust bearing shown in Fig. 4 with the apparatus for disposing of leakage applied thereto;

Fig. 7 is a plan view of an operating link and crank for operating the control gates;

Fig. 8 shows a turbine in which the bearing adjacent to the turbine is held by a cast spider instead of by radial bolts.

At the present time it is customary practice to hold an axial flow turbine in alignment by a steady bearing located just upstream from the runner hub, this bearing being held in alignment by a cast spider having fixed radial arms attached to the water trunk, as shown in Fig. 8. With such construction, however, the cast arms offer considerable resistance to the flow, and it is necessary to provide, in addition, some form of regulating gates upstream from the bearing spider, thus introducing obstructions to the flowing water at two or more places.

The preferred embodiment of my invention is illustrated in Fig. 1, in which 4 represents a blade of the turbine runner either built integral with, or removably attached to the hub 5 and rim 6, the latter revolving with close clearances between flanges 7 and 8 on the ends of penstock and draft tube, respectively. The runner hub 5 is keyed to the shaft 9 by key 10 and held against longitudinal movement on the shaft by a split ring 11.

The shaft 9 is held against longitudinal movement by the hub 12 which is keyed to the shaft and retained by an adjustable nut 13, this hub 12 in turn revolving against a thrust bearing surface 14 in the hub 2 of the spider 3, and is held in alignment by steady bearing linings 15 in the hub 2.

The hub 16 is provided with steady bear-

ing linings 17 and is held in true central position by bolts 18 passing through the penstock walls and held in tension by a nut at the outer end. The position of the bearings 5 may be adjusted by increasing and decreasing the tension on the oppositely disposed bolts, respectively. Bolts 18 may be used alone in lieu of the cast spider, but they are here shown also serving as pivot bolts 10 for sector-shaped gates 19, the details of which are later described.

The gates 19 are shown in open position to admit water to the turbine runner. When closed they overlap and touch each other 15 along their edges, thus forming a closed wall against the flow of water. A thrust is thus transferred to hub 16 by the pressure against the gates 19. This thrust can be resisted by bearing surfaces 20 against the 20 runner hub 5, from which it will be transferred through the shaft to hub 12, and thence through thrust bearing surfaces 14 to the fixed hub 2, but it is preferably transferred directly from fixed hub 16 25 to fixed hub 2 by means of a pipe 21 surrounding the shaft and attached to the hubs 16 and 2 by any appropriate means as tap bolts, stud bolts, pipe threads or the like. When the gates 19 are partially open, the 30 deflection of the flowing water causes a tendency to twist the hub 16, which stress is also readily transferred to fixed hub 2 through pipe 21.

Fig. 2 shows a fragmentary view of an installation, similar to that of Fig. 1, except that the runner is entirely within the water passage and power is transmitted by the shaft in the usual manner instead of directly from the rim of the runner as disclosed in Fig. 1. The construction of the 35 control gates and their operation is, however, similar to that previously described, the pipe 21 in this case being attached to any convenient fixed structure.

The method of operating the control gates 40 19 is illustrated in Figs. 5 and 7 in which 22 is a shift ring encircling the penstock similar in all respects to the shift ring of any hydraulic turbine of other design and similarly controlled by any standard governor 45 (not shown). A link 23 split in two parts and bolted together has a socket at each end, engaging at one end a ball 24 attached to the shift ring and at the other end, a ball 50 25 on the gate crank 26.

A circumferential movement of the shift ring 22 thus rotates, through an arc, the gate crank 26, which in turn is keyed or otherwise rigidly attached to the sleeve 27, which is either a part of, or rigidly attached to, the regulating gate 19, and its 55 movement therefore accomplishes the desired rotative adjusting movement of the regulating gate. The sleeve 27 is packed against leakage along its outer surface by

gland 28 and along its inner surface by gland 29. It will be understood that each of the gates 19 is similarly connected to the shift ring 22 so that they are all actuated simultaneously by movement of the ring. 70

A preferred method of reducing, trapping, and draining away the leakage through the clearance spaces between the rotating rim of the turbine 6 and the adjacent fixed flanges of the penstock 7 and draft tube 8 is illustrated in Fig. 5. From an inspection of this figure, it will be observed that 30 indicates outwardly convex collector rings or flanges attached at 36 to and rotating with the runner ring 6 and made water-tight by suitable gasket or water-proof compound, and positioned opposite the leakage clearances. 75

The rings 30 are nearly enclosed respectively by a similar internally grooved collector ring 31 attached to the penstock and a collector ring 32 attached to the draft tube, both rings 31 and 32 therefore being stationarily mounted to overlie the rotating rings 30 as shown. 80

When the unit is at rest, there will generally be a suction at all clearances since the gates 19 will be closed. If, however, tailwater is sufficiently high, an internal pressure may exist in the lower portion, or perhaps, in the entire turbine, in which case the leakage escaping into ring 30 around the lower half of the circumference will flow at once to the bottom at point 33. That water which escapes in the upper half of the circumference will flow around the outer surface of penstock or draft tube until it falls partially into inner groove 30 and partially into outer grooves 31 and 32. The former might accumulate at 33 in the bottom of the inner groove until it overflows into the outer groove and escapes through drain pipes 34, but preferably an uninterrupted suction would be applied to passages 35 which would drain the leakage from the inner ring and prevent overflow. Drain pipes 34 lead to a suitable sump maintained automatically at a low level regardless of height of the tailwater. 90

When the unit is revolving, a pressure 115 will exist in the penstock clearances and a suction in the draft tube clearances at the up and down stream sides respectively of the runner. The suction is objectionable, however, as it would admit air to the draft tube and destroy the full value of the draft head. To avoid this condition, water is piped to one or more points at or near the top of the draft tube flange and conveyed through passage 38 into an annular groove 39 under sufficient pressure to flow through the clearance into the draft tube. In some instances it may be preferable to divide this groove 39 by partitions disposed along radial lines, into several independent por- 120 125 130

tions of the total circumference and to supply water to each by means of individual pipes, in order to obtain sufficient pressure at top of groove 39 to prevent suction of air 5 into draft tube without unnecessarily high pressure at the bottom of groove 39.

Such water as escapes into the rotating rings 30 is held by centrifugal force in the periphery of these rings throughout their 10 circumferences until intercepted by the tips 40 of suction pipes 35, which are turned so that their open ends are directed against the approaching water, thus assisting the efforts of the applied suction. As many 15 pipes 35 as necessary may be provided.

Drainage pipes 34 preferably drain to a closed sump from which the water is automatically pumped and from which the air is exhausted by a fan during operation, thus 20 causing an inflow of air through the close clearance between grooved rings 30 and rings 31 and 32 and thereby preventing the escape of any possible spray produced by the leakage.

25 The leakage through the clearances at opposite sides of the runner ring is reduced to a minimum by making these clearances as small as practicable and may be further reduced by providing annular grooves 41 in 30 the fixed and rotating elements, which, as will be understood, offer an obstruction to the flow of water through these clearances.

In Fig. 3 I have shown a modified form 35 of my invention, in which the cast spider 42 carrying the thrust bearing 43, is positioned downstream from the turbine runner or in the draft tube instead of upstream in the penstock.

40 In Fig. 8 I have shown a fragmentary view of a turbine in which the central guide bearing is placed just upstream from the turbine, but rigidly supported by a cast spider 44. The other bearing in this construction would be a combined guide and 45 thrust bearing located either upstream of the runner as in Fig. 1, or downstream as in Fig. 3. In this structure, radial bolts similar to the bolts 18 previously described, may be employed in lieu of the cast spider, since 50 they offer less resistance to the flowing water than the large cast spider. If the control gates are not mounted on the radial bolts, other means of controlling the water flow will be required.

55 Fig. 4 illustrates another form of my invention in which the thrust bearing surface 46 is made of lignum vite, Babbitt, or other suitable bearing material mounted in the flange of the draft tube, and against which 60 the rim of the revolving turbine bears.

This construction is shown in detail in Fig. 6, in which all parts are similar to those of Fig. 5, except the bearing surface 46. The guide bearings of the runner shown in 65 Figs. 3 and 4 are without apparent means

for overcoming the torque on the bearing caused by the deflecting water when the gates are partly open and that caused by bearing friction. This torque can be effectively resisted by placing the pivot bolts in a 70 position not truly radial, i. e., tangential to a circle of a diameter somewhat less than the diameter of bearing hub; and by arranging them alternately to resist torque in opposite directions, the sector gates being shaped correspondingly at the ends to clear the hub and rim in rotating through the necessary angle of nearly 90 degrees.

All bearings illustrated could be of lignum 75 vitea or other durable wood, or of Babbitt or other suitable bearing material. Likewise, ball bearings or roller bearings of any standard design might be used and packed against admission of water or supplied with oil or grease under sufficient pressure to exclude 80 the water.

In Fig. 1 oil or grease would be supplied to any type of bearings 14 and 15 which might be adopted, through a passage 47 provided in the cast spider arm 3, from which it 90 would also find its way along the shaft through pipe 21 to bearing surfaces 17 and 20.

In the accompanying drawings, for simplicity, I have shown the rim of the turbine 95 rotor equipped with a belt pulley, but I contemplate equally any other power transmitting means as gear, rope sheave, or chain sprocket. I also contemplate mounting the poles of an electrical generator directly upon this rim and building the stator of the generator to enclose the same as disclosed in my pending application, to which reference has already been made.

100 It should be manifest from the foregoing that my invention is capable of embodiment in various constructions differing materially in their structural details; consequently, the scope of my invention is not to be circumscribed by the structures illustrated and described, but comprehends also such as are generically defined in the following claims.

I claim:

1. A hydraulic turbine comprising an 115 axial flow runner having a rim exteriorly accessible and forming a portion of the water conduit, a shaft for said runner, and bearings for said shaft arranged within said conduit and attached to the walls thereof.

2. In a hydraulic turbine, the combination 120 with an axial flow runner provided with a rim extending to the exterior of the turbine forming a portion of the water conduit, of a shaft extending longitudinally beyond said rim and upon which said runner is mounted, and bearings for said shaft arranged within said conduit and attached to the walls thereof.

3. A hydraulic turbine, comprising an 125 axial flow runner provided with an ex-

teriorly projecting rim forming a portion of the water conduit, a shaft upon which said runner is mounted, a bearing for said shaft arranged within said conduit, and means for adjustably supporting said bearing.

4. In a hydraulic turbine, the combination of a water conduit, an axial flow runner disposed in said conduit and provided with a rim forming a portion of said conduit, a central shaft disposed entirely within said conduit upon which said runner is mounted, a bearing within the conduit in which said shaft is journaled, radially disposed rods supporting said bearing, said rods being adjustable on the exterior of said conduit to adjust the position of said bearing, control gates pivotally mounted on said rods, and means outside said conduit for regulating the position of said gates.

5. In a hydraulic turbine, the combination of a water conduit, an axial flow runner mounted in said conduit and having a rim forming part of said conduit, a shaft upon which said runner is carried, a spider in said conduit providing a bearing for one end of said shaft, a bearing for the other end of the shaft, radially disposed rods connected with said last mentioned bearing and projecting through the walls of said conduit, means for regulating the tension of said rods to adjust the position of said bearing, radially disposed control gates carried by said rods, and means outside the conduit for simultaneously adjusting the position of all of said gates.

6. In a hydraulic turbine, the combination of an axial flow runner, a shaft, a bearing for said shaft, radially disposed rods adjustably supporting said bearing in position, control gates pivoted on said rods and provided with sleeves extending through the walls of the water conduit, and means outside said conduit connected with said sleeves whereby all of said gates may be simultaneously adjusted.

7. In a hydraulic turbine, the combination of a water conduit, a series of radially disposed control gates arranged within said conduit and provided with portions extending through the walls of said conduit, means for preventing leakage around said outwardly extending portions, radially disposed rods upon which said gates are pivotally mounted, a bearing adjustably carried by said rods, an arm attached to each of said outwardly extending portions, a ring surrounding said conduit, a ball and socket connection between said ring and each of said arms whereby movement of said ring circumferentially of the conduit will be transmitted to said gates to simultaneously adjust the position thereof, and a runner rotatably supported by said bearing.

8. In a hydraulic turbine, the combination of a water conduit, an axial flow runner disposed in said conduit and having a circumferential ring forming a section of said conduit, an annular collector ring attached to said runner and overlying the joint between said runner and said conduit, and means for removing the water collected in said ring.

9. In a hydraulic turbine, the combination of a water conduit, an axial flow runner disposed in said conduit and having a portion thereof forming a section of said conduit, a collector ring mounted on said runner and overlying the joint between said runner and said conduit, and a second collector ring mounted on said conduit and overlying said first mentioned ring.

10. In a hydraulic turbine, the combination of a conduit, an axial flow runner mounted in said conduit and having a portion thereof forming a section of said conduit, overlapping collector rings mounted on said conduit and runner, respectively, in which leakage through the joint between said runner and said conduit is collected, and means for removing the collected water from said collector rings.

11. In a hydraulic turbine, the combination of a water conduit, a hydraulic runner disposed in said conduit and having a peripheral portion forming a section of the conduit, and means for preventing the escape of water through the joints between said conduit and said runner, said means comprising overlapping convex rings mounted on the runner and on the conduit, respectively, and adapted to collect the leakage through said joints.

12. In a hydraulic turbine, the combination of a penstock and a draft tube disposed in spaced relation, a runner interposed between the opposed ends of said penstock and draft tube, and means for creating a pressure in the clearance between said runner and draft tube to prevent leakage of air through said clearance into said tube.

13. In a hydraulic turbine, the combination of a water conduit, a runner rotatably mounted in said conduit and having a circumferential ring forming a section of said conduit, and means for producing a water pressure in the clearance between a side of said runner ring and the opposed face of said conduit.

14. In a hydraulic turbine, the combination of a water conduit, a runner interposed in said conduit and adapted to be driven by water passing through said conduit, a clearance between said runner and a portion of the wall of said conduit, and means for supplying water under pressure to the clearance between said runner and conduit.

LEROY F. HARZA.
